UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-CONTROLLING DEVICE.

Application filed July 17, 1920, Serial No. 397,010. Renewed July 6, 1925.

The invention relates particularly to a device for controlling windows of the type generally used in closed cars and provides, among other objects, a device which may 5 be quickly and easily attached, which is concealed with the exception of the operating handle, which adapts the window to be easily adjusted to any desired position and which will automatically latch and unlatch the 10 window upon release and actuation of said handle respectively.

While the invention will be fully described in the following specification I do not wish to be limited to the preferred embodiment 15 shown, as in its broader aspects it is capable of embodiment in numerous forms.

In the drawing:

Figure 1 is an interior view of a closed vehicle door to which the invention is applied;

Figures 2 and 3 are a side and top view, in partial section of the device detached;

Figure 4 is a fragmentary side view showing the manner in which the device becomes 25 unlatched upon downward movement of the operating handle.

Describing the invention in detail, A is an automobile door, having in its upper portion a window opening A' for which a vertically 30 slidable glass plate A² forms a closure, the lower portion of said door being hollow as indicated at A³ and said glass being adapted to enter the chamber A³, when lowered. Within said chamber is located a 35 controlling device for the sliding glass, constituted as follows:

C is a bracket member comprising the right angle pieces C' and C² attached by screws B' to one of the uprights B of the 40 door. D is a stub shaft journalled in said bracket member and carrying the lifter arm E.

This lifter arm is mounted between the angle pieces C' and C² and is centrally 45 slotted to permit the installation of a counterbalance spring member comprising a plurality of springs F extending from points F' at the free end of the lifter arm to a common anchorage member G, secured to a pin 50 H positioned above the stub shaft D on said bracket member. These springs are tensioned to urge the lifter arm upwardly with a force substantially counterbalancing the 55 weight of the glass A², the counterbalancing effort being transmitted to the glass by a

roller I journalled upon the free end of the lifter arm and engaging a metal channel member J secured to the bottom edge of the glass.

An operating and automatic latch mechanism is provided for the device thus far described, as follows:

A rock arm M is pivoted upon a pin L carried by the lifter arm E at one side of the axis of said arm.

Said rock arm M is provided with a short rack of lateral teeth M' and with an enlarged portion M² slotted as indicated at M³ to engage the stub shaft D. As is shown in Figures 2 and 4, the portion M² provides opposed sockets N² and N³ for housing two coiled springs N and N' which oppositely abut against the stub shaft D. The function of these springs is to normally maintain the rock arm in the position shown in Figure 2, with the stub shaft equally spaced from the ends of the slot M³, in which position, the teeth M' on the quadrant will engage a relatively large rack of oppositely projecting teeth C³ on the bracket member C². X is a handle attached to the enlarged portion M² of the quadrant member by bolts Y, said handle being arranged adjacent the inner face of the door, all other parts being concealed within the chamber A³.

To operate the described device, the handle X is actuated in the direction in which it is desired to shift the glass A². Thus, if the handle is moved in a downward direction, as shown in Figure 4, the initial movement thereof due to the arm M will be independent of the lifter arm E, and will rock about its pivot L to the position shown in Figure 4, the spring N being compressed during such movement of the rock arm. The angle through which the rock arm swings is determined by the length of the slot M³, this distance of travel being sufficient to completely disengage the teeth M' and C³. Continued pressure upon the handle X will then swing the lifter arm E downward to the desired position, the handle then being released and through the medium of the equalizing springs N and N' being returned to its neutral or intermediate position automatically.

To move the arm E upward, a similar action of the parts takes place with the exception that the rock arm is swung in an opposite direction so that the spring N' is compressed 100 while the stub shaft D forms an abutment 105 110

for the opposite end of the slot M^3 and the teeth M' swing outwardly beyond the teeth C^3 to disengagement. It is to be noted that the rock arm M forms in effect a latch member which establishes a lost motion connection between the handle X and the lifter arm E , and which is normally maintained in latch engagement with the arcuate rack C^3 by the springs N and N' and is disengagable from said rack through taking up of said lost motion.

What I claim as my invention is:

1. A clutch for a window controlling device including a pivoted lifting element, and an actuating handle therefor, said clutch including a fixed latch member, and a second latch member pivotally mounted upon said lifting element and angularly adjustable to engage said fixed latch member, said second latch member being secured to said actuating handle, the axis of said second latch member being parallel to that of said lifting element, whereby release of said latch members and shifting of said lifting element is effected by a movement of said actuating handle constant in direction.

2. A clutch for a window controlling device including a pivoted lifting element and an operating handle, said clutch including a toothed rock arm pivotally mounted upon said lifting element and secured to said operating handle, a fixed arcuate rack, and means acting upon said rock arm for holding the teeth thereof normally in mesh with said rack to latch said lifting element, the axis of said rock arm being parallel to that of said lifting element whereby release of said rock arm and rack and shifting of said lifting element is effected by a movement of said handle constant in direction.

3. A clutch for a window controlling device including a pivoted lifting element and a handle, said clutch including a toothed rock arm pivoted to said lifting element and slotted to engage the pivot thereof and having secured thereto said handle, a stationary arcuate rack, and spring means normally maintaining said rock arm in a position engaging its teeth with said rack, said rock arm forming a lost motion connection between said handle and lifting element and being rocked to a position disengaging its teeth from said rack upon initial actuation of said handle.

4. A clutch for a window controlling device including a bracket member, a lifting element pivotally mounted thereon and an actuating member for said lifting element, said clutch including a toothed member forming a lost motion connection between said actuating member and lifting element, the teeth of said bracket member adapted to engage said toothed member, and opposed springs acting on said toothed member and abutting against the pivot for said lifting

element to automatically hold said toothed member normally in a position engaging its teeth with those of said bracket member, said teeth being disengageable through taking up of the lost motion upon initial movement of said actuating member.

5. A clutch for a window controlling device including a pivoted lifting element, said clutch comprising a latch member pivoted to said lifting element and slotted for engagement with the pivot of said lifting element, a fixed latch member, and means acting upon said pivoted latch member for holding the same normally engaged with said fixed latch member.

6. A clutch for a window controlling device, including a pivotal lifting element and an actuating handle for said lifting element having a lost motion connection therewith, said clutch including a toothed latch member movably carried by said lifting element, a fixed arcuate rack co-axial with said lifting element and engageable by the teeth of said latch member in one position of the latter, means yieldably maintaining said latch member normally in said position said latch member being actuatable through taking up of lost motion in the connection between said handle and lifting element to initially disengage said latch member from said rack when said handle is operated.

7. A clutch for a window controlling device including a pivotal lifting element and actuating member therefor, said clutch including a rock arm pivoted upon said lifting element and forming a latch member therewith, an arcuate rack co-axial with said lifting element and engageable by said latch member, and means normally maintaining said latch member yieldably engaged with said rack, said actuating member having a lost motion connection with said lifting element through said latch member adapted while taking up lost motion to disengage said latch member from said rack.

8. A clutch for a window controlling device, including a pivotal lifting element and an actuating member therefor, said clutch including a pivotal latch member upon said lifting element and slotted to engage the pivot thereof, the slot extremities limiting rocking of said latch member on its pivot, spring means normally maintaining said latch member in intermediate position and an arcuate rack normally engaged by said latch member in said intermediate position, said actuating member having a lost motion connection with said lifting element through said latch member and adapted to shift said latch member out of engagement with said rack through the initial taking up of lost motion.

9. A clutch for a window controlling device including a pivoted lifting element and an operating handle therefor, said clutch in-

- cluding a latch member pivotally mounted upon said lifting element and secured to said handle, a stationary latch member and means acting upon said pivotal latch member for normally engaging the same with said stationary latch member, the axis of said pivotal latch member being parallel to that of said lifting element, whereby release of said latch members and shifting of said lifting element is effected by a movement of the handle constant in direction.
10. A clutch for a window controlling device including a pivoted lifting element and an actuating handle therefor, said clutch including a latch member pivotally mounted upon said lifting element and slotted to engage the pivot thereof, and also secured to said handle, a stationary latch member co-acting with said pivotal latch member, and spring means normally maintaining said pivotal latch member engaged with said stationary latch member, said pivotal latch member forming a lost motion connection between said handle and lifting element and being actuatable out of engagement with said stationary latch member through the initial movement of said handle.
11. A clutch for a window controlling device including a bracket member, a lifting element pivotally mounted thereon and an actuating member for said lifting element, said clutch including a stationary latch member formed upon said bracket member, a second latch member mounted upon said lifting element and forming a lost motion connection between said actuating member and said lifting element, a pair of opposed springs engaging the pivot of said lifting element at opposite sides of the pivot and abutting against said second latch member to automatically hold the same normally engaged with said stationary latch member, said second latch member being actuatable out of engagement with said stationary latch member through initial actuation of said handle.
12. A clutch for a window controlling device including a pivoted lifting element, said clutch including a latch member pivoted upon said lifting element and limited in its pivotal movement by engagement with the pivot of said lifting element, a fixed latch member, and means acting upon said pivoted latch member for holding the same normally engaged with said fixed latch member.
13. A clutch for a window controlling device, including a pivotal lifting element, a pivotal support therefor and an actuating handle for said lifting element, said clutch including an arcuate rack upon said support concentric with the pivot of said lifting element and a latch member connected to said lifting element and slotted longitudinally thereof to engage the pivot of said lifting element, said latch member normally engaging said rack and being actuatable clear of said rack by said handle preliminary to actuation of said lifting element by said handle.
14. A clutch for a window controlling device including a pivotal lifter arm, a supporting bracket therefor and an actuating handle for said lifter arm, said clutch including a rack upon said bracket concentric with the pivot of said lifter arm and remote from the pivot, a latch member connected to said lifter arm normally engaging said rack and slotted longitudinally for movement clear of said rack, said handle acting upon said lifter arm through said latch member and initially shifting the latter clear of said rack.
15. A clutch for a window controlling device including a pivotal lifter arm, a support therefor and an actuating handle for said arm, said clutch including a rack upon said support concentric with the pivot of said arm, and a single latch member upon said arm and normally engaging said rack to hold said arm from movement in either direction, said handle being movable in either direction through a path parallel to said arm for initially releasing said latch member and subsequently actuating said arm.
16. A clutch for a window controlling device including a pivotal lifter arm and an actuating handle therefor, said clutch including a rack concentric with the pivot of said arm, a latch member upon said arm and normally engaging said rack, said handle being movable through a path parallel to said arm for initially releasing said latch member and subsequently actuating said arm, a counterbalancing spring for normally moving said arm in one direction, and a single support for the entire mechanism.

In testimony whereof I affix my signature.

STANLEY W. NICHOLSON.
